(57) **CLAIM**

The ornamental design for a rotary dryer, as shown and described.

DESCRIPTION

FIG. 1 is a front left side elevational view of a rotary dryer in an open configuration showing my new design;

FIG. 2 is a left side elevational view thereof, with the right side being a mirror image thereof;

FIG. 3 is a front elevational view thereof;

FIG. 4 is a top plan view thereof;

FIG. 5 is a bottom left side perspective view of the rotary dryer of FIG. 1 in a closed configuration;

FIG. 6 is a front elevational view of the rotary dryer of FIG. 5;

FIG. 7 is an enlarged bottom plan view of the rotary dryer of FIG. 5;

FIG. 8 is an enlarged top plan view of the rotary dryer of FIG. 5;

FIG. 9 is an enlarged bottom left side perspective view of the upper central portion of the rotary dryer of FIG. 1, shown for clarity of disclosure;

FIG. 10 is an enlarged bottom left side perspective view of the end portion of an arm of the rotary dryer of FIG. 1, shown for clarity of disclosure;

FIG. 11 is a front left side elevational view of an alternative embodiment of a rotary dryer in an open configuration showing my new design;

FIG. 12 is a left side elevational view of the alternative embodiment of FIG. 11, with the right side being a mirror image thereof;

FIG. 13 is a front elevational view of the alternative embodiment of FIG. 11; and,

FIG. 14 is a top plan view of the alternative embodiment of FIG. 11.
